UNITED STATES PATENT OFFICE

168,862

LAMP BASE

William S. Sawle, III, Evanston, Ill.

Application November 8, 1952, Serial No. 22,197

Term of patent 14 years

(Cl. D48—20)

To all whom it may concern:

Be it known that I, William S. Sawle, III, a citizen of the United States, residing at Evanston, in the county of Cook and State of Illinois, have invented a new, original, and ornamental Design for a Lamp Base, of which the following is a specification, reference being had to the accompanying drawing forming a part thereof.

In the drawing:

Fig. 1 is a perspective view of a lamp base showing my new design;

Fig. 2 is a top plan view thereof;

Fig. 3 is a front elevational view; and

Fig. 4 is a side elevational view.

I claim:

The ornamental design for a lamp base, substantially as shown.

WILLIAM S. SAWLE, III.
